(57) **CLAIM**

The ornamental design for a wine bottle cooler, as shown and described.

DESCRIPTION

FIG. 1 is a top left isometric view of the wine bottle cooler of the present invention;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is a bottom right isometric view thereof; and,

FIG. 9 is a top isometric view thereof, illustrating a wine bottle in the wine bottle cooler.

The broken lines shown in FIG. 7 and the areas within them depict portions of the wine bottle cooler that form no part of the claimed design. The broken lines shown in FIG. 9 depict environmental subject matter that forms no part of the claimed design.
